UNITED STATES PATENT OFFICE.

ARCHIBALD G. SHAVER, OF CHICAGO, ILLINOIS, AND ALLEN B. KENDALL, OF NIAGARA FALLS, NEW YORK, ASSIGNEES TO THE REGAN SAFETY DEVICES COMPANY, INC., OF NEW YORK, N. Y., A CORPORATION OF NEW YORK.

TRAIN-CONTROL SYSTEM.

Application filed December 18, 1922. Serial No. 607,684.

To all whom it may concern:

Be it known that we, ARCHIBALD G. SHAVER and ALLEN B. KENDALL, citizens of the United States, and residents, respectively, of Chicago, county of Cook, State of Illinois, and Niagara Falls, county of Niagara, and State of New York, have invented certain new and useful Improvements in Train-
Control Systems, of which the following is
a specification.

This invention relates to a train control system, and more particularly to improvements in a system for controlling the movement of trains; and has special reference to the provision of a system in which manual operation of the train by the engineman is coordinated with the operation of the train by automatic control mechanism to provide for expeditious movement of trains under absolute safe conditions.

A principal object of the present invention comprehends the provision of a system consisting of an improvement on the train control system described and claimed in the copending application of Archibald G. Shaver Serial No. 292,548 of April 25, 1919, in which the engineman is permitted to exercise full control of the operation of the train so long as he is alert and acting in the proper performance of his duties; in which when the engineman is incapacitated or is remiss in the performance of his duties he will be supplanted by the automatic train control mechanism; and in which the engineman may modify the action of the automatic mechanism under certain conditions to keep the train in motion provided he is alert, and provided further that the movement of the train has been reduced to a safe running speed.

A further and more specific object of the present invention relates to the provision of a train control system in which the movement of the vehicle is controlled within the limits of three permissible speeds including a maximum speed beyond which the vehicle cannot run, a medium speed under which the vehicle must approach points of danger and run in localities where a greater speed would be unsafe, and a low speed above which the vehicle cannot run in unsafe localities, as in blocks occupied by other trains. In accomplishing this object of the invention, the design and construction of the system is such

that the maximum and medium permissible speeds are automatically controlled from the roadside without possibility of interference by the engineman; and with low permissible speed is controlled by the combined action of the automatic mechanism and the engineman on the train, the action of one supplementing the action of the other to permit an expeditious train operation without sacrifice of safety.

A still further object of the present invention relates to the provision of a system of the nature referred to in which manual operation of the train control mechanism is made impossible under those conditions of train operation which fall within the scope of control of the automatic mechanism, manual control being made possible only when the activity of the engineman and the train control mechanism is desired under "danger" traffic conditions.

To the accomplishment of the foregoing and such other objects as may hereinafter appear, our invention consists in the elements and their relation one to the other, as hereinafter particularly described and sought to be defined in the claims, reference being had to the accompanying drawings showing a preferred embodiment of our invention, and in which:

The figure is a diagrammatic view showing the vehicle carried apparatus and circuits and the roadside apparatus and circuits cooperating therewith.

In the train control system of our present invention, for directly controlling the movement of the train there is provided an electro-responsive device for controlling the operation of the air brake system, the said electro-responsive device being under the control of the cooperating train and roadside mechanism, and being operated thereby in accordance with roadside or traffic conditions. The electroresponsive vehicle control device comprises an electromagnet 20 which controls the operation of a combined reservoir and brake valve 21 of the type disclosed in the patent of Archibald G. Shaver No. 1,411,526 of April 4, 1922, and in the copending application of Allen B. Kendall Serial No. 443,046 of February 7, 1921, the said reservoir and brake valve being interposed between the main reservoir 22 of the air brake system and the engineman's brake

valve 23, and being connected thereto by means of the piping 24 and 25 respectively, the said reservoir and brake valve 21 including a reservoir valve which under normal conditions permits the free flow of reservoir air from the main reservoir 22 to the engineerman's brake valve 23, and which under unsafe running conditions of the train is closed to cut off the supply of air from the main reservoir to the engineman's brake valve. The combined reservoir and brake valve 21 is also connected by means of the pipe 26 to the brake pipe of the air brake system, and by means of a pipe 27 to atmosphere, the construction and operation of these parts being such that under normal running conditions of the train the brake valve of the valve mechanism 21 is closed to prevent venting communication between the brake pipe and the exhaust pipe 27, and under abnormal running conditions of the train the said valve is opened to effect inter-communication between the pipes 26 and 27 for venting the brake pipe to apply the brakes.

For the purpose of rendering the automatic train control mechanism inactive, as when it is desired to run the train without automatic control, there is provided a bypass 28 connecting the pipes 24 and 25, the said bypass being controlled by a valve 29 which is normally closed and which is shown in closed position in the figure, the opening of the valve 29 permitting the free flow of reservoir air from the main reservoir 22 to the engineman's brake valve 23, irrespective of any operation of the combined reservoir and brake valve 21; and there is also provided a cock 30 in the piping 26, the said cock being normally open and being closed when it is desired to render inoperative the control of the brake valve of the reservoir and brake valve 21.

As disclosed in the above mentioned patent to A. G. Shaver, in the operation of the system the electromagnet 20 is energized under "safe" roadside conditions, and is de-energized under unsafe roadside conditions to effect the desired operations of the reservoir and brake valve mechanism 21. For directly controlling the operation of the electromagnet 20, there is provided a train carried circuit which is normally energized by a train carried source of energy such as the battery 35, the said circuit including the resistance r leading from the positive terminal of the battery 35, conductors 36, 37 and 38, a contact 39 which is movable to any of a plurality of positions such as a , b and c shown in the figure, and which normally occupies the inclined full line position as shown in said figure, contact point 40, conductor 41, contact point Z , a speed circuit controller 42, connected to the wheels of the vehicle and operated thereby, a com-

mon contact point 43, conductor 44, the coil of the electromagnet 20, conductor 45, a contact point 46, a manually operable switch 47 normally making contact with said contact point 46, conductors 48, 49 and 50, to the negative terminal of battery 35. With this construction, it will be seen that this controlling circuit is normally closed for effecting the energization of the electromagnet 20 when the contact 39 is in the full line position A as indicated, and when the circuit controller contacts Z and 43 are bridged by the circuit controller 42. The contact 39 is closed as hereinbefore referred to and as will be described presently in detail, when the train is running under "safe" roadside conditions and the contacts Z and 43 of the speed circuit controller are so adjusted as to keep this circuit closed when the train is running below a predetermined maximum speed, such for example as 60 or 70 miles an hour, and to open the circuit when the speed of the train exceeds this predetermined maximum.

To control the behaviour of the contact 39, there is provided cooperating train and roadside mechanism which functions to cause the said contact 39 to maintain or hold its full line position a under "safe" traffic conditions, and to cause the same to move to the inclined dotted line position c under "caution" track conditions, and to assume the neutral vertical dotted line position b under "danger" traffic conditions. The train and roadside mechanism for controlling the action of the contact 39 includes the provision of a roadside energy transmitting device which in the present form of our invention comprises a plurality of ramp rails spaced along the roadside, a ramp rail such as indicated at 51 being provided for each section or block of the track, the said ramp rail comprising means for transmitting energy to a train carried shoe mechanism 52 under "safe" roadside conditions, such energy being transmitted to a translating device such as a relay 53, the action of which directly controls the behaviour of the contact 39. Under normal running conditions of the train with the train running between ramp rails, the translating device 53, which may comprise a stick relay of the type disclosed in the copending application of Allen B. Kendall Serial No. 414,375 of August 18, 1920, and which includes an electromagnetic locking device 54 is energized by the train carried battery 35 through a local circuit including the said battery, the resistance r , conductors 36 and 55, contact 56 in full line position shown, conductor 57, contacts 58 and 59 normally bridged by a switch element 60 attached to for movement with the shoe 52, conductor 61, the relay and relay lock 53 and 54, conductor 62, contacts 63 and 64 normally bridged by a switch element 65

also attached to for movement with the shoe 52, the conductor 66, relay contact 67 in the full line position shown, and conductors 68 and 50 to the negative pole of the battery 35.

When the train passes a ramp under "clear" roadside conditions, the translating device or stick relay 53 is controlled by the cooperation of the shoe 52 and the ramp rail 51, the cooperation being such that as the shoe 52 rides over the ramp 51 the normally closed local train circuit for the relay 53 is opened and another circuit substituted therefor, which other circuit is operated in response to roadside or traffic conditions. The substituted circuit comprises a partial roadside circuit which is connected to the ramp 51 and a partial train carried circuit which is connected to the shoe 52, the two partial circuits combining to form a completed circuit for operating the relay 53. In the present construction the partial roadside circuit includes essentially a roadside source of energy such as the battery 69, a pole changer including the movable contacts 70 and 71 under the control of a relay magnet R, a circuit make and break device 72 also under the control of the relay R, and one of the track rails T, the said circuit being traced from the ramp 51 by the conductor 73, the make and break contact 72, the conductors 74 and 75, contact 71 in full line position shown, conductors 76 and 77, battery 69, conductors 78 and 79, contact 70 in full line position shown, conductor 80, resistance 81, conductor 82, a switch means 83 controlled by the operation of the roadside signal 84 as will be described presently, and a conductor 85 electrically connected to one of the rails T. The partial cooperating vehicle circuit may be traced from the shoe 52 which contacts the ramp 51 through the conductor 86, contact 87 which is connected to the contact 59 by means of the switch element 60 bridging the same when the shoe 52 is raised by engagement with the ramp 51, the contact 59, conductor 61, stick relay and lock therefor 53 and 54, conductor 62, contact 63, a contact 88 connected thereto by means of the switch element 65 which bridges these contacts upon elevation of the shoe 52, and conductor 89 connected to the framework of the vehicle. With this construction and arrangement, it will be evident that when the shoe 52 engages a ramp 51 the relay 53 will be controlled by a circuit which is completed by the engagement of the shoe and the ramp and the electrical connection between the vehicle framework and the track rail T. Under normal running conditions of the vehicle, the contacts 70 and 71 of the roadside pole changer are in the position shown in the figure, making circuit at their front contact points, and under this condition the cooperating vehicle and road-

side partial circuits form a completed closed circuit for energizing the stick relay 53 with current of a given direction or polarity to hold or maintain the relay contacts such as 56, 67 and 39 in the full line position shown in the drawings. With this construction, it will furthermore be apparent that as the shoe 52 leaves the ramp 51 under "clear" roadside conditions, the local or vehicle circuit for controlling the relay 53 will be re-substituted for the combined roadside and vehicle partial circuit for energizing the said relay to maintain the contacts thereof in the normal full line position.

As heretofore referred to, one of the principal objects of the present invention relates to the provision of a train control system in which the train is under the control of a plurality of permissible speeds such as maximum, medium and low speeds, and in which the maximum and medium permissible speeds are controlled automatically by the roadside mechanism without possibility of interference by the engineman, and the low permissible speed is controlled by the combined action of the automatic mechanism and the engineman on the train, the action of one supplementing the action of the other to permit an expeditious train operation without any sacrifice of safety. To accomplish this object of our invention, the contact 39 is caused to assume the dotted line position c under "caution" traffic conditions, and the vertical or neutral dotted line position b under "danger" traffic conditions, movement of the contact to the position c being effective for automatically placing the train controlling electromagnet 20 under the control of the speed of the train, movement of the contact to the neutral position b being effective for deenergizing the said electromagnet 20 to apply the brakes, instrumentalities being provided operable manually by the engineman and only under such "danger" traffic conditions for effecting the re-energization of the electromagnet 20 under safe running conditions of the train.

For effecting the movement of the contact 39 to the inclined position c under "caution" track conditions, the relay 53 is energized by a current having a direction opposite to that of the normal energizing current, the relay 53 comprising to this end a three-position relay of the type where with current transmitted in one direction to the coil thereof, the contacts will be moved and held in one position as shown in the full lines in Fig. 1, while with the current transmitted in a reverse direction the contacts will be moved and held in another position as shown by the inclined dotted lines in the figure, and where with no current transmitted for energizing the relay 53, the contacts will assume the vertical or neutral dotted line position shown in the figure.

Under "caution" track conditions the relay 53 is energized by current of an opposite direction or polarity when the shoe 52 contacts the ramp 51, the combined circuit 5 formed by the partial roadside vehicle circuits controlling the action of the relay being energized from the roadside battery 69 with current flowing in a direction opposite to the normal flow thereof, this reversal 10 of direction of current being accomplished by movement of the contacts 70 and 71 of the roadside pole changer, effecting the opening of the front contact points thereof and the closing of the back contact points so as 15 to connect the contact 70 to the positive terminal of the battery 69 by means of the conductors 77 and 90, and to connect the contact 71 to the negative terminal of the battery 69 by means of the conductors 78 and 20 91, this operation being accomplished by the energization of the relay R with current having a direction opposite to the normal flow of current in said relay as disclosed for example in the patent to A. G. Shaver 25 1,505,062 of August 12, 1924. When the shoe 52 leaves the ramp 51 under these "caution" conditions, the relay 53 remains energized by a current of opposite polarity, this relay being controlled by the battery 35 and energized by means of the circuit including the resistance r, conductors 36, 37 and 38, contact 67 in dotted line position, conductor 66, contacts 64 and 63, conductor 62, relay lock 30 and relay 54 and 53, conductor 61, contacts 35 59 and 58, conductor 57, contact 56 in dotted line position, conductors 92, 68 and 50 to the negative terminal of the battery 35.

When the stick relay 53 is thus energized, the contact 39 assumes the position c for 40 placing the operation of the electromagnet 20 under the control of the speed of the vehicle. This is accomplished by means of a circuit controlled by the contact 39, the said circuit including train battery 35, resistance 45 r, conductors 36, 37 and 38, contact 39 in the position c, conductor 93, speed contact Y open when the speed of the train exceeds a predetermined medium limit and closed by the speed circuit controller 42 when the 50 speed of the train is at or below the said predetermined limit, contact 43, conductor 44, electromagnet 20, conductor 45, contact 46, manual control switch 47, conductors 48, 49 and 50 to the negative terminal of the battery 35. With this construction it will therefore be seen that the existence of "caution" track conditions will effect an automatic application of the brakes if the speed of the train is above a predetermined medium limit such as will cause the opening of the contact Y, and if the train is running below the said predetermined medium speed limit when the train passes a "caution" ramp the "caution" indication will be impressed upon the train by the movement of 60 65

the contact 39 so that if the speed of the train thereafter exceeds the predetermined limit, an application of the brakes will take place, the construction being therefore such that the train is automatically controlled 70 under "caution" traffic conditions without permitting intervention on the part of the engineman.

As hereinbefore described, the contact 39 is caused to assume the neutral position b 75 under "danger" traffic conditions, and it will be noted from a consideration of the said figure that when the said contact assumes the position b, the main controlling circuit and the speed controlling circuit for the 80 electromagnet 20 are both opened so as to effect a deenergization of the electromagnet and an application of the brakes of the vehicle to bring the vehicle to a halt. For causing the contact 39 to assume the neutral 85 position, the relay 53 is deenergized when the shoe 52 rides on the ramp 51, this deenergization being controlled by the opening of the make and break contact 72 of the roadside mechanism which is controlled by 90 deenergization of the relay R in response to "danger" traffic conditions.

For the purpose of preventing a full stop of the vehicle under "danger" traffic conditions, we provide means operable for forestalling a full stop, the said means being manually operable by the engineman, and being rendered operative only after the "stop" effect has been initiated by the operation of the automatic mechanism and after a predetermined stage of said "stop" effect of the vehicle has been reached which corresponds to a safe running condition of the vehicle under "danger" traffic conditions. The forestalling means of our present invention is furthermore so designed that a mis-operation thereof, as under "clear" and "caution" roadside conditions, will not affect the running operation of the vehicle, the said forestalling mechanism being rendered operable only under "danger" traffic conditions. More specifically, the forestalling means of our present design includes the provision of mechanism for controlling the movement of the vehicle by a predetermined low speed of the vehicle, a low speed control circuit for the electromagnet 20 being provided to this end, the said speed control circuit comprising the train battery 35, resistance r, conductors 36, 37, 94 and 95, contact point 96, a normally open manually controlled contact 97, conductor 98, speed circuit controller contact X corresponding to a predetermined low speed of the vehicle normally open and closed by the speed circuit controller 42 under low speed conditions, the common contact 43, conductor 44, electromagnet 20, conductor 45, contact point 46, switch contact 47, and conductors 48, 49 and 50. This circuit is normally open at two contact points 100 105 110 115 120 125 130

96 and X, the former requiring a manual operation of the engineman, and the latter requiring a reduction in the speed of the vehicle to or below a predetermined low and safe limit.

For manually closing the contact 97, there is provided circuit means including a stick relay 99 and its stick contact 100, a normally open make and break device 101 which comprises a special contact under the control of the stick relay 53, and a manually operable switch 47 heretofore referred to, this circuit being open under "clear" and "caution" operating conditions at the contact 101, the said contact 101 assuming the non-closing positions a' and c' under "clear" and "caution" conditions, and the circuit closing position $b'-b^2$ when the relay 53 is deenergized in response to "danger" traffic conditions. The contact member 101 and its contacts are merely diagrammatically illustrated and comprises in construction a fork member, the forks of which are resilient and normally engage contact points in the positions b' and b^2 . When this fork contact member is urged in one direction one contact position, for example b' , is opened, and when urged in the opposite direction the other contact position b^2 is opened. When an operation for an application of the brakes takes place under "danger" traffic conditions with the contact $b'-b^2$ in circuit closing position, the stick relay 99 is in a condition to be energized, and will be energized upon pushing of the switch 47 by the circuit comprising battery 35, resistance r , conductors 36, 37, 94 and 102, make and break contact $b'-b^2$ closed, conductor 103, electromagnet 99, conductor 104, back contact point 105, switch contact 47, and conductors 48, 49 and 50. With this circuit arrangement it will be noted that only under "danger" operating conditions will this circuit be in a condition to be closed by operation of the manual switch 47, and when this manual switch is accidentally closed under "clear" and "caution" operating conditions this circuit will not be closed to change the operating status of the other vehicle circuits.

Upon the closing of this circuit under the prescribed conditions, the contacts 100 and 97 controlled by the relay 99 are closed, the contact 100 forming a stick contact for the relay 99 so that when the circuit is in a condition to be closed the manual switch 47 may be released and the circuit held closed by the shunt provided by the contact 100 and conductor 106. With the circuit devised, it will be furthermore seen that when the make and break contact $b'-b^2$ is again opened as when the same is moved either to the position a' or c' , the stick circuit will open at the contact 100 so that a further operation of the manually controlled switch

47 will again be necessitated to forestall a subsequent stop.

Thus when a "stop" effect of the train is produced in response to "danger" traffic conditions, the operation of the switch 47 manually by the engineman will permit the forestalling of a full stop by the closing of the contact 97, such forestalling being, however, only rendered effective when the vehicle speed has been reduced to or below a safe low limit controlled by the speed circuit controller contact X, expeditious train operation being thereby made possible by the alertness of the engineman without any sacrifice of safety in train running.

It is a further object of our invention to provide a track or roadside mechanism in which any defect in the roadside mechanism, as when the ramp 51 is destroyed or any part of the ramp circuit torn, is made known to the engineman by an indication of the roadside signalling apparatus so that he may properly control the operation of his train, and in which the roadside mechanism is conversely made to reflect the behaviour of the signalling apparatus. To these ends there is provided a detecting circuit for the roadside ramp 51, the said detecting circuit including the conductor 107 connected to the ramp, a relay 108 which controls the operation of the signalling apparatus 84, a conductor 109, contact 110 under the control of relay R, conductor 80, pole changing contacts 70 and 71, battery 69, and the conductors associated therewith, conductor 74, contact 72 and conductor 73 back to the ramp 51. For reflecting the behaviour of the signalling apparatus 84 in the ramp 51, there is provided the movable switch element 83 heretofore referred to, the said switch element being connected for movement with the signal 84, the said switch element 83 maintaining the circuit controlled thereby closed through an arc 112 closed from 48° to 90° so that when the signal 84 indicates "clear" and "caution" the circuit to the ramp 51 is closed, and when the said signal indicates "danger", the said circuit is opened to transmit a "danger" indication to the vehicle carried mechanism.

The operation of our improved train control system will in the main be fully apparent from the above detailed description thereof. It will be apparent that under "clear" and "caution" roadside conditions the stick relay 53 will be operated by a flow of current in normal and opposite directions respectively to effect the operation of the train carried mechanism to produce under normal and "clear" roadside conditions the continued energization of the electromagnet 20, energization of this electro-magnet being further under the control of a maximum speed limit of the vehicle and the contact Z of the speed circuit controller 42, and under

“caution” track conditions to place the operation of the electromagnet 20 under the control of a medium speed limit of the vehicle controlled by the contact Y, the vehicle carried mechanism being solely under automatic control if the train is operated inconsistent with the demands of the road. It will be furthermore apparent that under “danger” traffic conditions the electromagnet 20 is deenergized to bring the vehicle to a halt, and that if the engineman is alert the complete halt of the vehicle may be foreshadowed by a positive act on his part and an operation of the switch 47, the forestalling, however, being rendered possible only after the speed of the train has been reduced to a low controlling speed, which may for example be from 10 to 15 miles an hour, the operation of the vehicle under “danger” traffic conditions being therefore under the combined control of the automatic mechanism and the engineman to produce expeditious train movement.

While we have shown our device in the preferred form, it will be obvious that many changes and modifications may be made in the structure disclosed without departing from the spirit of the invention, defined in the following claims.

30 We claim:

1. In a train control system, in combination, an electrically operated vehicle control device, a vehicle circuit therefor for normally energizing the same, provisions including roadside mechanism active for opening the said circuit to effect deenergization of said device, and vehicle provisions for re-energizing the said device comprising circuit means including a make and break device closed upon the opening of the first circuit, a speed controlled contact device closed when the train reaches a speed below a predetermined limit, and a normally open switch means closed by a manual operation of the engineman and openable only by a break in the circuit at the said make and break device.

2. In a train control system, in combination, an electrically operated vehicle control device, a vehicle circuit therefor for normally energizing the same, provisions including roadside mechanism active for opening the said circuit to effect deenergization of said device, and vehicle provisions for re-energizing the said device comprising a circuit means including a make and break device closed upon the opening of the first circuit, a speed controlled contact device closed when the train reaches a speed below a predetermined limit, and a normally open switch means closed by a manual operation of the engineman including instrumentalities for holding the switch means closed only when the said make and break device is closed.

3. In a train control system, in combina-

tion, an electrically operated vehicle control device, a vehicle circuit therefor for normally energizing the same, provisions including roadside mechanism active for opening the said circuit to effect deenergization of said device, and vehicle provisions for re-energizing the said device comprising a circuit means including a make and break device closed upon the opening of the first circuit, a speed controlled contact device closed when the train reaches a speed below a predetermined limit, and a normally open stick relay switch means closed by a manual operation of the engineman and openable only by a break in the circuit at the said make and break device.

4. In a train control system, in combination, an electrically operated vehicle control device, a vehicle circuit therefor for normally maintaining the said device in a given condition, provisions including roadside mechanism active for operating the said circuit to change the condition of the said device, and vehicle provisions for returning the said device to its normal condition comprising circuit control instrumentalities including a make and break device closed upon the operation of the said circuit, a speed controlled contact device controlled by the speed of the train, and a normally open switch means closed only by a manual operation and held closed only when the said make and break device is closed, whereby the said vehicle control device after an automatic operation thereof may be restored to its normal condition when the train reaches a speed below a predetermined limit and after the engineman operates the switch.

5. In a train control system, in combination, an electrically operated vehicle control device, a vehicle circuit therefor for normally maintaining the said device in a given condition, provisions including roadside mechanism active for operating the said circuit to change the condition of the said device, and vehicle provisions for returning the said device to its normal condition comprising circuit control instrumentalities including a make and break device closed upon the operation of the said circuit, a speed controlled contact device controlled by the speed of the train, and a normally open switch means closed only by a manual operation and openable automatically by the opening of said make and break device, whereby the said vehicle control device after an automatic operation thereof may be restored to its normal condition when the train reaches a speed below a predetermined limit and after the engineman operates the switch.

6. In a vehicle control system, in combination, a vehicle control device, a normally closed vehicle circuit therefor for normally energizing the same, a second normally open circuit therefor including a speed controlled

- contact means, provisions including roadside mechanism active for automatically opening the first circuit and automatically closing the second circuit under "caution" 5
- track conditions to place the device under a vehicle speed control and for opening the first circuit without closing the second circuit under "danger" track conditions to deenergize the said device to bring the vehicle 10 to a stop, and vehicle provisions for re-energizing the said device to forestall the stop, the said provisions being inoperative under normal conditions and being rendered operative only after the said first mentioned circuit 15 has been opened.
7. In a vehicle control system, in combination, a vehicle control device, a normally closed vehicle circuit therefor for normally energizing the same, a second normally open 20 circuit therefor including a speed controlled contact means, provisions including roadside mechanism active for automatically opening the first circuit and automatically closing the second circuit under "caution" track 25 conditions to place the device under a vehicle speed control and for opening the first circuit without closing the second circuit under "danger" track conditions to deenergize the said device to bring the vehicle to a stop, and vehicle provisions for re-energizing the said device to forestall the stop, the said 30 provisions being inoperative under normal conditions and being rendered operative only when both of said circuits are open.
- 35 8. In a vehicle control system, in combination, a vehicle control device, a normally closed vehicle circuit therefor for normally energizing the same, a second normally open circuit therefor including a speed controlled 40 contact means, provisions including a vehicle carried shoe mechanism and a roadside ramp mechanism active for opening the first circuit and closing the second circuit under "caution" track conditions to place the device 45 under a vehicle speed control and for opening the first circuit without closing the second circuit under "danger" conditions to deenergize the said device to bring the vehicle to a stop, and vehicle provisions for 50 re-energizing the said device to forestall the stop, the said provisions being inoperative under normal conditions and being rendered operative only after the said first mentioned circuit 55 has been opened.
9. In a vehicle control system, in combination, a vehicle control device, a normally operative vehicle circuit therefor for normally maintaining said device in a given 60 condition, a second normally inactive circuit therefor including a speed controlled contact means, provisions including roadside mechanism active for automatically rendering the first circuit inoperative and the second circuit active under "caution" track conditions and for rendering the first circuit

inoperative without rendering the second circuit active under "danger" track conditions to change conditions of the said vehicle control device and maintain the same changed, and vehicle provisions for again 70 returning said device to its said given condition, the said provisions being normally inoperative and being rendered operative only after said first mentioned circuit has 75 been rendered inoperative.

10. In a vehicle control system, in combination, a vehicle control device, a normally operative vehicle circuit therefor for normally maintaining said device in a given condition, a second normally inactive circuit therefor including a speed controlled contact means, provisions including roadside mechanism active for automatically rendering the first circuit inoperative and the second circuit active under "caution" 80 track conditions and for rendering the first circuit inoperative without rendering the second circuit active under "danger" track conditions to change the conditions of the said vehicle control device and maintain the 85 same changed, and vehicle provisions for again returning said device to its said given condition, the said provisions being normally inoperative and being rendered operative only when both of said circuits have 90 been rendered inoperative.

11. In a vehicle control system, in combination, a vehicle control device, a normally closed vehicle circuit therefor for normally energizing the same, a second normally open 100 circuit therefor including a medium speed controlled contact means, provisions including roadside mechanism active for automatically opening the first circuit and closing the second circuit under "caution" track 105 conditions to place the device under a vehicle medium speed control and for opening the first circuit without closing the second circuit under "danger" track conditions to deenergize the said device to bring the vehicle to a stop, and vehicle provisions for re-energizing the said device to forestall the stop, the said vehicle provisions being rendered active only after the device has been 110 deenergized for effecting the stop and after the speed of the train has been reduced below a predetermined low speed.

12. In a vehicle control system, in combination, a vehicle control device, a normally closed vehicle circuit therefor for normally energizing the same, a second normally open circuit therefor including a medium speed controlled contact means, provisions including roadside mechanism active for opening the first circuit and closing the second circuit under "caution" track conditions to place the device under a vehicle medium speed control and for opening the first circuit without closing the second circuit under "danger" track conditions to deenergize the 120 125 130

said device to bring the vehicle to a stop, and vehicle provisions for reenergizing the said device to forestall the stop comprising a third circuit including a low speed controlled contact device and a normally open make and break device capable of being closed only when the vehicle control device is operated under "danger" track conditions, and manually operated means for effecting the closing of said make and break device.

13. In a vehicle control system, in combination, a vehicle control device, a normally closed vehicle circuit therefor for normally energizing the same, a second normally open circuit therefor including a medium speed controlled contact means, provisions including a vehicle carried shoe mechanism and a roadside ramp mechanism active for opening the first circuit and closing the second circuit under "caution" track conditions to place the device under a vehicle medium speed control and for opening the first circuit without closing the second circuit under "danger" track conditions to deenergize the said device to bring the vehicle to a stop, and vehicle provisions for re-energizing the said device to forestall the stop comprising a third circuit including a low speed controlled contact device and a normally open make and break device capable of being closed only when the vehicle control device is operated under "danger" track conditions, and manually operated means for effecting the closing of said make and break device.
14. In a vehicle control system, in combination, a vehicle control device, a normally operative vehicle circuit therefor for normally maintaining the said device in a given condition, a second normally inactive circuit therefor including a medium speed controlled contact means, provisions including roadside mechanism active for rendering the first circuit inoperative and the second circuit active under "caution" track conditions and for rendering the first circuit inoperative without rendering the second circuit active under "danger" track conditions to

change the condition of the said vehicle control device to bring the vehicle to a stop, and vehicle provisions for returning the said device to its said given condition to forestall the stop comprising a third circuit including a low speed controlled contact means and a normally open make and break device capable of being closed only when the vehicle control device is operated under "danger" track conditions, and manually operated means for effecting the closing of said make and break device.

15. In a train control system, in combination, a train control device, a vehicle circuit controlling the same, provisions including a vehicle shoe mechanism and a roadside ramp mechanism for controlling the operation of the said vehicle circuit, roadside means for energizing the ramp mechanism under "safety" track conditions and for deenergizing the same under "danger" track conditions, the deenergization of said ramp mechanism being effective for operating the said circuit to produce a train stopping effect in the train control device, and vehicle provisions for forestalling a full train stop comprising a second circuit for said train control device including a normally open make and break device and a speed controlled contact device closed when the train reaches a predetermined low speed, and a manually controlled means for effecting the closing of said make and break device rendered operative only when the train control device is operated in response to "danger" track conditions.
